BENDING MACHINE

John Hollfelder, Belleville, N. J.

Application August 19, 1940, Serial No. 353,213

7 Claims. (Cl. 153—21)

This invention relates to metal bending, cutting, stamping and like machines and, more particularly, to a fluid operating means therefor.

In the past, the actuating mechanism of such machines comprised heavy and costly gearing or a fluid actuating mechanism which was complicated and required a very high fluid pressure.

An object of this invention is to provide a metal bending, cutting, stamping or like machine with a fluid pressure actuating mechanism which requires low pressure.

Another object of the present invention is to provide a simple and inexpensive actuating mechanism for a metal bending or like machine.

A still further object of the invention is to provide a machine of this character in which the actuating mechanism is durable and which will readily carry out the work for which it is designed.

Other objects of the invention will become apparent in the course of the following specification.

The above and other objects of the present invention are accomplished by providing a metal bending, stamping, cutting or like machine having a frame with a stationary die thereon and a movable die cooperating with said lower die and guided between guides on said frame, said movable die having a fluid pressure (such as compressed air) actuating means comprising an actuating plate resting on a diaphragm of resilient material, preferably rubber, the actuating plate being raised and lowered when fluid pressure is admitted and released from a chamber beneath the diaphragm, the actuating plate having levers connected thereto which are normally out of engagement with arms on the movable die but which may be brought into engagement with said arms to move the movable die away from the stationary die when fluid pressure is applied to the diaphragm, so that the metal to be bent, cut or stamped may be positioned over the bottom die, the movable die being returned when the pressure is released. The actuating plate also has pressure applying levers thereon which levers are adapted to engage the movable die arms when the first-mentioned levers are not in engagement with them and press the movable die against the metal to be bent, cut or stamped when fluid pressure is applied to the diaphragm.

The invention will appear more clearly from the following detailed description when taken in connection with the accompanying drawings,

showing by way of example a preferred embodiment of the invention.

In the drawings:

Figure 1 is a front elevational view, the machine being shown in its normal inoperative position;

Figure 2 is a view similar to Figure 1, the movable die being shown positioned away from the stationary die, the fluid pressure operating means being shown inflated;

Figure 3 is a front elevational view, showing the position of the various parts of the machine during the bending, cutting or stamping operation;

Figure 4 is a sectional view taken on the line 4—4 of Figure 1;

Figure 4a is an enlarged view of the lower left-hand corner of Figure 4; and

Figure 5 is an end elevational view of the machine taken on the line 5—5 of Figure 1.

Like numerals refer to like parts throughout the several views.

The machine of this invention comprises a bottom plate 10 rectangular in shape, having a raised border 10a around the same.

A rectangular sheet of resilient material 15, preferably rubber, substantially the same size as the bottom plate, is placed over the bottom plate 10, the outer edges of said sheet 15 covering the border 10a. Channel members 11 and 12 are mounted along the sides of the plate 10 over the sheet 15 and on the border 10a, bolts 16 passing through the bottom of the channel members 11 and 12, through the sheet 15 and into the border 10a. End channel members 13 and 14 are mounted across the opposite ends of the bottom plate 10 over the sheet 15 and on the border 10a, bolts 17 passing through the bottom of channel members 13 and 14, through the sheet 15, and into the border 10a.

The bolts 16 and 17 are drawn tightly so that the edges of the sheet 15 are held tightly between the bottoms of the channel members 11, 12, 13 and 14 and the border 10a, forming a fluid-tight chamber 18 below the sheet 15.

An actuating plate 19, substantially co-extensive with the enclosure formed by the channel members 11, 12, 13 and 14, rests on top of the sheet 15. A lining sheet 20 of soft, pliable resilient material, preferable rubber, substantially the same size as the bottom of the actuating plate is fastened to the said bottom to prevent chafing between the sheet 15 and the actuating plate and to prevent the sheet 15 from becoming

pinched between the actuating plate 19 and channel members upon inflation thereof.

Mounted on the end channels 13 and 14, respectively, are upright supports 21 and 22, there being a vertically extending space 23 in the support 21 and a vertically extending space 24 in the support 22, said spaces being in longitudinal alignment with one another.

End frame pieces 25 and 26 are fastened to the supports 21 and 22, respectively, as are side frame pieces 27 and 28, these frame pieces acting as guards to prevent persons from coming in contact with the moving, end-mechanisms of the machine.

Parallel longitudinally extending frame pieces 29 and 30 extend between the supports 21 and 22, and have a space 31 therebetween substantially centrally between the top and bottom of the upright supports 21 and 22.

A table 32 is mounted on top of the parallel frame pieces 29 and 30 and has mounted thereon a longitudinally extending stationary die 33.

Mounted for vertical movement above the stationary die 33 is a movable die 34, extending longitudinally between the supports 21 and 22, having a projection 35 extending through the space 23 in the support 21 and projecting beyond said support and guided in its up and down vertical movement by guide plates 36 and 37 on opposite sides of the space 23. Likewise, the movable die 34 has a projection 38 on the opposite end thereof, said projection extending through the space 24 and beyond the support 22 and is guided in its vertical movement by guide plates 39 and 40 mounted on the support 22 on opposite sides of the space 24.

The movable die 34 has backing plates 41 and 42 on opposite sides thereof held in position by bolts 43.

Pivottally mounted on the projections 35 and 38, respectively, and projecting downwardly therefrom are actuating bars 44 and 45. The bar 44 has a rectangular shaped aperture 46 therein and a semi-circular shaped surface 47 on the lowermost end thereof, while the bar 45 has a rectangular shaped aperture 47 therein and a semi-circular shaped surface 48 on the lower end thereof.

Rotatably mounted on the frame piece 29 on opposite ends thereof are wheels 49 and 50. A longitudinally slidabale rod 51 mounted in guides 52 and 53 is pivottally connected at one end to the top of the wheel 50 at 51a, while the opposite end thereof is pivottally connected to a link 54 which, in turn, is pivottally connected at 55 to the wheel 49.

Pivottally connected on the top of the wheel 49 and extending through the upright support 21 and slidably supported in an aperture 56 in said support is a shifting lever 57 having an enlarged head 58 adapted to engage the arm 44. On the top of the wheel 50, is pivottally connected at 51a a shifting lever 59 having an enlarged head 60 adapted to engage the arm 45. The lever 59 is slidably supported in an aperture 61 in the upright 22.

A crank 62 is connected to the wheel 50, the crank in turn having pivottally fastened to the end thereof at 63 a lever 64, the opposite end of which is pivoted at 65 to a pedal 66 pivoted at 67 to the base of the machine. The pedal 66 is adapted to be lowered against the tension of the spring 68, one end of which is fastened to the channel member 11 and the other end connected to the pedal.

Mounted on opposite sides of the actuating plate 19 in substantially the center thereof are upwardly extending bars 69 and 69a, having cross-arms 70 and 70a fixedly mounted thereon.

5 A link 71 is pivottally mounted at 71a to one end of the cross-arm 70, the link being pivottally connected to another link 72 which is pivottally connected to a short link 73, in turn, connected to one end of a crank 74. The crank 74 is pivoted at 75 in substantially the center thereof to the upright 21, the opposite end of the crank having an arm 76 therein extending outwardly beyond the upright 21. The links 71 and 72 are adjustable in respect to one another by means of the adjustment holes 77.

The opposite end of the upright 70 is connected to a crank 78 pivottally mounted at 79 on the upright 22, said connection being through a link 80, one end of which is pivottally connected to the cross-bar 70 and the opposite end pivottally connected to a link 81, said links being adjustable in relation to one another through the adjustment holes 82 therein. The opposite end of the link 81 is connected to a short link 83 pivottally connected to the upper part of the crank 78.

25 The lower end of the crank 78 has an outwardly extending arm 84 secured thereto, which extends beyond the upright 22.

The link system above described is duplicated 30 on the opposite side of the machine connecting one end of the cross-arm 70a to a crank pivottally mounted in the upright 21 adjacent the crank 74 and similar thereto. A roller 85 is rotatably mounted between the arm 76 and a like arm on the crank on the opposite side. Likewise, the opposite end of the cross-arm 70a is connected through links similar to links on the opposite side of the machine, as above described, to a crank 78a pivottally mounted in the upright 22 adjacent the crank 78 and similar thereto, there being a roller 86 rotatably mounted between the arm 84 and a similar adjacent arm 84a on the opposite side of the machine, which arm is secured to the aforementioned crank 78a.

45 The link 80 and the similar link on the opposite side of the machine are adapted to engage in their upward movement idler rollers 100 on opposite sides of the machine. The link 71 and the link similar thereto on the opposite side of the machine are adapted to respectively engage in their upward movement the idler rollers 101 and 101a.

Pivottally mounted at 87 in a slot 88 on the top of the actuating plate 19 is a pressure lever 89 which extends diagonally upwardly from the top of said plate through the space 23 in the upright 21 and through the rectangular aperture 46 in the bar 44, the end of the lever 89 being hooked at 90 to engage the bottom of the aperture 46.

60 Intermediate its ends the pressure lever 89 is pivoted on the pivot 91 to the frame pieces 29 and 30.

In a slot 92 on the top of the actuating plate 19 is pivottally mounted at 93 another pressure lever designated by the reference numeral 94, which lever extends diagonally upwardly from the top of the plate through the space 24 in the upright 22 and through the rectangular aperture 47 in the bar 45. The end of the lever 94 is hooked at 95 to engage the bottom of the aperture 47. Intermediate its length the lever 94 is pivoted at 102 to the frame pieces 29 and 30.

A fluid inlet pipe line 96 leads from a fluid supply source and is connected to the chamber

18. The inlet pipe line 96 has a control valve 97 therein.

An exhaust pipe line 98 having a fluid release valve 99 therein is likewise connected to the chamber 18.

The normal inoperative position of the various parts of the machine of this invention is illustrated in Figure 1 of the drawings. When it is desired to operate this machine to bend, cut, or stamp a sheet of metal, the upper die 34 must be moved away from the lower die 33, so that the metal may be placed therebetween.

It will be readily understood that cutting or stamping dies may be substituted for the bending dies 33 and 34 illustrated in the drawings.

To raise the upper die 34, it is necessary for the operator to first step on the foot pedal 66, which moves the lever 64 and the crank 62 downwardly, turning the wheel 50 in a counter-clockwise direction. The turning of the wheel 50 in a counter-clockwise direction slides the rod 51 to the left, as shown in Figure 1 of the drawings, which through the link 54 turns the wheel 49 in a clockwise direction, sliding the shifting lever 57 to the right, causing the arm 44 to swing outwardly to the dotted position shown in Figure 1 of the drawings. Likewise the counter-clockwise movement of the wheel 50 slides the shifting lever 59 to the left, causing the arm 45 to swing outwardly to the position shown in dotted lines in Figure 1. In this position, the bottom of the aperture 46 in the arm 44 is out of the path of the hooked portion 90 of the pressure lever 89, as is the bottom of the aperture 47 of the arm 45 out of the path of the hooked portion 95 of the pressure lever 94. The arms 44 and 45 may move upwardly and the hooked portions 90 and 95 move downwardly without the hooked portions and arms contacting one another.

The operator retains his foot on the foot pedal 66 and admits fluid pressure into the chamber 18 beneath the diaphragm 15 by turning the control valve 97, allowing the fluid pressure to enter from the source through the inlet pipe 96. As the chamber 18 becomes filled with the fluid, the rubber diaphragm 15 is caused to move upwardly, which causes the actuating plate 19 also to move upwardly. Upward movement of the actuating plate 19 moves the cross-arm 70 and 70a upward causing the links 71 and 80 to engage the idling rollers 101 and 100, respectively, which will cause the crank 74 and the arm 76, which is secured thereto, to move in a counter-clockwise direction around the pivot 75 until the roller 85 engages the semi-circular surface 47 on the lowermost end of the arm 44. Simultaneously therewith, the crank 78 is moved in a clockwise direction around the pivot 79, which raises the arm 84, bringing the roller 86 into contact with the semi-circular surface 48 on the lowermost end of the arm 45.

When the rollers 85 and 86 engage the ends of the arms 44 and 45, respectively, foot pressure is released from the pedal 66, the spring 68 returning the shifting lever mechanism to its normal position. Further fluid pressure admitted to the chamber 18 will raise the upper die to the position shown in Figure 2 of the drawings.

The admission of fluid pressure beneath the diaphragm 15 causes the lining sheet 20, which is of a soft, pliable resilient material, to spread, which fills in any gap existing between the sides and ends of the actuating plate 19 and the channel members 11, 12, 13 and 14, as shown

at 103 in Figures 2 and 3 of the drawings. This prevents the rubber diaphragm 15 from becoming pinched between the channel members and the actuating plate.

5 When the upper die 34 has been moved upwardly to the desired position, fluid pressure from the source is cut off by shutting the valve 97, which will maintain the pressure beneath the actuating diaphragm 15 holding the actuating plate against further movement. The metal to be bent is then positioned between the top die 34 and the bottom die 33. The fluid pressure is then released from the chamber 18 by opening the release valve 99 and allowing the pressure 10 to exhaust from the chamber 18 through the exhaust pipe line 98. As the pressure is exhausted from the chamber 18, the diaphragm 15 and the actuating plate 19 on top thereof moves downwardly. Downward movement of the actuating plate 19 causes the cross arms 70 and 70a to move downwardly, the links 71, 72 and 73 moving the crank 74 and arm 76, which is secured thereto, in a clockwise direction around the pivot 75, lowering the roller 85. Simultaneously therewith 15 the crank 78 is moved in a counter-clockwise direction around the pivot 79 through the links 80, 81, 83, lowering the roller 86.

As the rollers 85 and 86 are lowered, the movable upper die 34 is lowered by gravity, since the arms 44 and 45 pivoted to opposite ends of the die 34 are in engagement with the rollers 84 and 85, respectively. The arms 44 and 45 remain in contact with the rollers 84 and 85 until the upper die 34 engages the metal to be bent, which was placed over the lower die 33 when the upper die 34 was in its uppermost position, as above described, the upper die coming to rest on the metal. Further downward movement of the rollers 85 and 86 causes the arms 44 and 45 to 20 become disengaged therefrom and swing inwardly to the position shown in full lines in Figure 1 of the drawings. In this position the upper die 34 is resting on the metal to be bent, the metal being over the lower die 33.

45 To bend the material, fluid pressure is again admitted to the chamber 18, causing the actuating plate 19 to rise. The pressure lever 89, by the raising of the actuating plate 19, is pivoted in a clockwise direction about the pivot 91, the pressure lever 94 being pivoted in a counter-clockwise direction about the pivot 93. Since the arms 44 and 45 are now in the line of movement of the pressure of levers 89 and 94, the hooked portion 90 on the lever 89 engages the bottom 50 of the aperture 46 in the arm 44, while the hooked portion 95 on the pressure lever 94 engages the bottom of the aperture 47 in the arm 45. Further upward movement of the actuating plate 19 will cause the arms 44 and 45 to move 55 downwardly and thereby cause the upper die 34 to be pressed against the material over the bottom die 33, bending the material. The position of the parts of the machine during the bending operation is shown in Figure 3 of the drawings. 60

65 Fluid pressure from the chamber 18 is then released through the exhaust pipe line 98 by opening the release valve 99, returning the machine to its inoperative position, as shown in Figure 1 of the drawings.

70 It is apparent that the specific illustrations shown have been given by way of illustration and not by way of limitation and that the structure above described is subject to a wide variation and modification without departing from the scope or intent of the invention, all of which

variations and modifications are to be included within the scope of the present invention.

What is claimed is:

1. In a machine of the class described having a frame, a fixed die mounted on said frame, a movable die cooperating with said fixed die, a fluid pressure actuating mechanism for actuating said movable die comprising a diaphragm of resilient material mounted over a base in fluid-tight relation thereto and adapted to be inflated and deflated by means of fluid pressure, actuating means removably connected to said movable die, said actuating means being actuated by said diaphragm when the same is inflated to move said movable die away from said fixed die under fluid pressure and actuated when the diaphragm is deflated to permit said movable die to return to said fixed die, and pressure exerting means connected to said actuating means and adapted to be connected with said movable die when said actuating means is disconnected therefrom so that fluid pressure on said diaphragm will cause said pressure exerting means to move the movable die toward the fixed die under fluid pressure.

2. In a machine of the class described having a frame, a fixed die mounted on said frame, a movable die cooperating with said fixed die, a fluid pressure actuating mechanism for actuating said movable die comprising a diaphragm of resilient material mounted over a base in fluid-tight relation thereto and adapted to be inflated and deflated by means of fluid pressure, actuating means actuated by said diaphragm when the same is inflated, connecting means pivotally mounted on said movable die and adapted to be removably connected with said actuating means to move the movable die by fluid pressure away from said fixed die and to permit said movable die to return to said fixed die by gravity when the diaphragm is deflated, and pressure exerting means connected to said actuating means and adapted to be connected with said movable die when said connecting means is disconnected therefrom, whereby fluid pressure on said diaphragm will cause said actuating means and the pressure exerting means to move the movable die toward the fixed die under fluid pressure.

3. In a machine of the class described having a frame, a fixed die mounted on said frame, a movable die cooperating with said fixed die, arms pivotally mounted on opposite ends of said movable die, a diaphragm comprising a sheet of rubber mounted over a base on said frame in fluid-tight relation thereto and adapted to be inflated and deflated by means of fluid pressure, an actuating plate actuated by said diaphragm when the same is inflated and deflated, connecting means operable by said diaphragm, means for bringing said arms into connection with said connecting means to move said movable die away from said fixed die when said diaphragm is inflated and to permit said movable die to return to said fixed die by gravity when the diaphragm is deflated, and pressure exerting means operable by said actuating plate and adapted to engage said arms when said connecting means is disconnected therefrom, whereby fluid pressure on said diaphragm will cause said actuating plate and pressure exerting means to move the movable die toward the fixed die under fluid pressure.

4. In a bending machine having a base, a frame mounted on said base, a fixed die mounted on said frame, a movable die cooperating with said fixed die, guides on said frame guiding said movable

die, arms pivotally mounted on opposite ends of said movable die, a chamber in said base, a diaphragm comprising a sheet of resilient material mounted over said chamber in fluid-tight relation thereto, and adapted to be inflated and deflated by means of fluid pressure, an actuating plate actuated by said diaphragm when the same is inflated and deflated, connecting means operable by said diaphragm, means for bringing said arms into connection with said connecting means to move said movable die away from said fixed die when said diaphragm is inflated and to permit said movable die to return to said fixed die by gravity when the diaphragm is deflated, and pressure exerting means operable by said actuating plate and adapted to engage said arms when said connecting means is disconnected therefrom, whereby fluid pressure on said diaphragm will cause said actuating plate and pressure exerting means to move the movable die toward the fixed die under fluid pressure.

5. In a bending machine having a base, a frame mounted on said base, a fixed die mounted on said frame, a movable die cooperating with said fixed die, arms pivotally mounted on opposite ends of said movable die, a chamber in said base, a diaphragm comprising a sheet of resilient material mounted over said chamber in fluid-tight relation thereto and adapted to be inflated and deflated by means of fluid pressure, an actuating plate actuated by said diaphragm when the same is inflated and deflated, cranks pivotally mounted on said frame adjacent the opposite ends thereof each of said cranks being adapted to engage one of said pivotally mounted arms, links connecting said cranks to said actuating plate, means for bringing said arms into engagement with said cranks whereby said movable die may be moved away from said fixed die when said diaphragm is inflated and to permit said movable die to return to said fixed die by gravity when the diaphragm is deflated, and pressure exerting means operable by said actuating plate and adapted to engage said arms when said cranks are not in engagement therewith, whereby fluid pressure on said diaphragm will cause said actuating plate and pressure exerting means to move the movable die toward the fixed die under fluid pressure.

6. In a bending machine having a base, a frame mounted on said base, a fixed die mounted on said frame, a movable die cooperating with said fixed die, arms pivotally mounted on opposite ends of said movable die, a chamber in said base, a diaphragm comprising a sheet of rubber mounted over said chamber in fluid-tight relation thereto, and adapted to be inflated and deflated by means of fluid pressure, an actuating plate actuated by said diaphragm when the same is inflated and deflated, cranks pivotally mounted on said frame adjacent the opposite ends thereof each of said cranks being adapted to engage one of said pivotally mounted arms, links connecting said cranks to said actuating plate, shifting levers adapted to engage said pivotally mounted arms and bring the same into the path of movement of said cranks whereby said movable die may be moved away from said fixed die when said diaphragm is inflated and returned to said fixed die by gravity when the diaphragm is deflated, and pressure exerting means operable by said actuating plate and adapted to engage said arms when said cranks are not in engagement therewith, whereby fluid pressure on said diaphragm will cause said actuating plate and pressure exerting means to move the movable die toward the fixed die under fluid pressure.

7. In a bending machine having a base, a frame mounted on said base, a fixed die mounted on said frame, a movable die cooperating with said fixed die, arms pivoted on opposite ends of said movable die, a chamber in said base, a diaphragm comprising a sheet of rubber mounted over said chamber in fluid-tight relation thereto and adapted to be inflated and deflated by means of fluid pressure, an actuating plate actuated by said diaphragm when the same is inflated and deflated, cranks pivotally mounted on said frame adjacent the opposite ends thereof each of said cranks being adapted to engage one of said pivoted arms, links connecting said cranks to said actuating plate, shifting levers adapted to engage

10
15

said pivoted arms and bring the same into the path of movement of said cranks, whereby said movable die may be moved away from said fixed die when said diaphragm is inflated and returned to said fixed die by gravity when the diaphragm is deflated, pressure exerting levers each pivoted intermediate its length to said frame and connected at one end to said actuating plate the opposite ends being adapted to engage said pivoted arms when said cranks are not in engagement therewith whereby fluid pressure on said diaphragm will cause said actuating plate and pressure exerting means to move the movable die toward the fixed die under fluid pressure.

JOHN HOLLFELDER.
